UNITED STATES PATENT OFFICE.

JAMES A. BECHER, OF MISHAWAKA, INDIANA.

ENGINE.

SPECIFICATION forming part of Letters Patent No. 754,277, dated March 8, 1904.

Application filed May 6, 1903. Serial No. 155,874. (No model.)

To all whom it may concern:

Be it known that I, JAMES A. BECHER, a resident of Mishawaka, in the county of St. Joseph and State of Indiana, have invented certain new and useful Improvements in Engines; and I do hereby declare the following to be a full, clear, and exact description of the invention, such as will enable others skilled in the art to which it appertains to make and use the same.

10 My invention relates to an improvement in engines, and more particularly to engines having oscillating pistons, the object of the invention being to provide an improved engine of this character which will be extremely compact and well balanced and on a rigid short compact bed and which will be simple in construction and operation; and it consists in certain novel features of construction and combinations and arrangements of parts, as will be 15 more fully hereinafter described, and pointed out in the claims.

In the accompanying drawings, Figure 1 is a side view illustrating my improvements. Fig. 2 is a view in section on the line *xx* of Fig. 1, 20 and Fig. 3 is a view in longitudinal section.

1 represents the engine-bed, which comprises a base-plate and a vertical central web 2, having strengthening-flanges at its top and edges, as shown. The web 2 has bearings for the 30 crank-shaft 3 and also for the hub 4 of my improved engine cylinder or chamber 5. This chamber comprises a hollow cup 6, having a central hollow cylindrical extension or hub 4 on one side secured in the bearing on web 2, and this cup has an external flange 7, to which a plate 8 is secured by bolts or screws and closes the cup forming the engine cylinder or chamber, and said plate 8 has a bearing 9, alining with the hub 4, which together form 35 the bearings for the drive-shaft 10. The drive-shaft 10 has a crank-arm 11 secured thereon, and a pitman 12 connects this crank-arm 11 with a crank-pin 13 on one side of a heavy wheel 14 on the crank-shaft 3, which latter is supported in the bearing on web 2 of bed 1.

On opposite sides of the cylinder 5 steam-chests 15 are secured, and reciprocating valves 16 are located in these steam-chests 15 and are 50 operated as will now be explained.

A bracket 17 is secured to the upper portion of the cylinder and provides a bearing for a shaft 18, on which a walking-beam 19 is secured, and valve-rods 20 are pivotally secured to the ends of this walking-beam 19, pass 55 through packing-rings and nuts 22 in the top of steam-chests 15, and have the valves 16 secured thereon. A depending arm 23 is secured on shaft 18 and is pivotally connected at its lower end to a pitman 24, provided with a 60 ring frame or strap 25, mounted on an eccentric 26 on shaft 3, so that as the shaft 3 is revolved the eccentric will operate the walking-beam to reciprocate the valves.

On shaft 10 in the cylinder an oscillating piston 27 is secured and comprises a sleeve keyed to the shaft and radial blades 28, snugly engaging the walls of the cylinder, and stops 29 are located in the cylinder to limit the turning movement of the piston and serve the same 65 functions as the cylinder-heads of an ordinary reciprocating piston-engine. These stops 29 have exhaust-ports 30 therein, and ports 31 and 32 are provided above and below the stops and alternately serve as inlet and exhaust ports, according to the position of the valves.

The operation of my improvements is as follows: As shown in Fig. 3, the live steam is about to enter port 32 on one side and port 31 on the other and exhaust the steam through 70 the ports 30, and as the piston-blades are forced around they will, through the medium of oscillating arm 11, turn crank-shaft 3 and eccentric 26, which latter will move pitman 24, arm 23, and walking-beam 19. This movement of the walking-beam will depress one 75 valve 15 and elevate the other to change their positions and reverse the flow of the steam to return the piston to its former position, and so on, the oscillating movement of the arm 11 80 serving to revolve the crank-shaft 3, and the 85 operation of the valves is automatic.

A great many changes might be made in the general form and arrangement of the parts described without departing from my invention, 90 and hence I do not confine myself to the precise details set forth, but consider myself at liberty to make such slight changes and alterations as fairly fall within the spirit and scope 95 of my invention.

Having fully described my invention, what I claim as new, and desire to secure by Letters Patent, is—

1. The combination with an engine-bed comprising a bed-plate and an upright web thereon, of a cylindrical chamber having a hub on one side secured in a bearing on the web, a shaft projecting through the hub into the chamber, an oscillating piston on the shaft in the chamber, an arm on the shaft at one side of the web, and means for automatically regulating the admission and exhaust of steam from the chamber to oscillate the piston.
2. The combination with an engine-bed having an upright web and bearings on said web, of an engine-cylinder having a hub on one side secured in one of said bearings, a crank-shaft mounted in the other of said bearings, a shaft extending through the hub into the cylinder, an oscillating piston on the shaft in the cylinder to operate the shaft, an arm on the shaft, on one side of the web opposite to the cylinder, and a pitman connecting said arm with the crank-shaft.
3. The combination with an engine-bed hav-

ing a vertical web, of a engine-cylinder having a hub on one side secured in a bearing on the web to support the cylinder on one side of the web, a crank-shaft supported across the web, an oscillating piston in the cylinder, a shaft driven thereby and projecting through the hub, an arm on the shaft, at one side of the web opposite to the cylinder, a pitman connecting said arm with the crank-shaft, an eccentric on the crank-shaft on the same side of the web as the cylinder, a pitman reciprocated by the eccentric, a bracket on the cylinder, a shaft in said bracket, a walking-beam on said shaft, an arm on said shaft connected with the last-mentioned pitman, and reciprocating valves for the cylinder operated by the walking-beam.

In testimony whereof I have signed this specification in the presence of two subscribing witnesses.

JAMES A. BECHER.
